TOTE TRAY

Jack Evans, Des Plaines, Ill., assignor to Century Display Manufacturing Company, Inc., Chicago, Ill., a corporation of Illinois

Application June 3, 1955, Serial No. 36,346

Term of patent 14 years

(Cl. D58—12)

Fig. 1 is a perspective view of a tote tray, showing my new design;

Fig. 2 is a top plan view of the tote tray; and

Fig. 3 is a side elevation of the tote tray.

I claim:

The ornamental design for a tote tray, as shown.
